UNITED STATES PATENT OFFICE

2,159,681

HAT

Lauren Otho Wisman, Walnut Creek, Calif., assignor to E. D. Bullard Company, San Francisco, Calif., a corporation of California

Original application March 9, 1937, Serial No. 129,853. Divided and this application September 27, 1937, Serial No. 165,841

3 Claims. (Cl. 2—3)

This is a division of my co-pending application Serial No. 129,853, filed March 9, 1937.

My invention relates to safety hats; and the broad object of the invention is to provide a hat formed from a single blank of hard compacted sheet material.

A further object of the invention is to provide an improved mounting for the sweat band and head straps.

10 The invention possesses other objects and features of advantage, some of which, with the foregoing, will be set forth in the following description of my invention. It is to be understood that I do not limit myself to this disclosure of species 15 of my invention, as I may adopt variant embodiments thereof within the scope of the claims.

Referring to the drawing:

Figure 1 is a side elevational view of a hat embodying the improvements of my invention; and 20 Figure 2 is a bottom view of the same.

Figure 3 is a sectional view showing details of the sweat band and head strap mounting.

In terms of broad inclusion, the safety hat of 25 my invention comprises a one-piece crown and brim of hard compacted fibrous material. The crown is of dome shape, and the integrally formed brim extends outwardly from the lower portions of the crown. A sweat band is provided in the hat, and pivoted supporting tabs are 30 provided for fastening the band to the crown. Head straps are also arranged in the crown, and are connected to the supporting tabs.

In greater detail, and referring to the drawing, the hat of my invention comprises a dome shaped crown 2 and an integrally formed brim 3, pressed from a single blank of hard compacted sheet material. The sheet used is preferably a 35 densely compacted fibrous material, such as vulcanized fiber; this material being of light weight 40 while at the same time having great strength and rigidity. This type of sheet material has been used in the past for making safety hats of sectional construction, sewn or otherwise secured together. These sectional hats are weaker mechanically, and are bulkier and heavier than a one-piece hat would be. The sectional construction has been generally employed however, because of the difficulty experienced in forming the hat from one piece.

50 I have succeeded however in making a hat from a single blank of hard compacted sheet material, by the method disclosed in my co-pending application, Serial No. 129,853, filed March 9, 1937. Such a one-piece hat, as shown 55 in Figure 1, has a dome shaped crown 2,

bounded along its lower portions by an outwardly projecting annular brim 3 extending around the entire hat. The crown is preferably provided with ventilating openings 4. These openings are formed by cutting slits in the crown and pressing the dome portions above the crown surface to open the slits. After the hat is formed it is painted, or otherwise treated, for waterproofing.

A sweat band 6 and head straps 7 are provided in the hat. As shown in Figures 2 and 3 the 10 head straps 7 and sweat band 6 are fastened to the upper and lower ends respectively of a plurality of supporting tabs 8. The latter are preferably of a relatively stiff material, such as celluloid, and are pivotally connected intermediate 15 their ends to the crown by suitable rivets 9. Sweat band 6 is also preferably of a relatively stiff flexible material, adapted to shape itself to the head of the wearer. A band of Celluloid has been employed with good results, and is preferably 20 used.

The sweat band is detachably connected to the lower ends of supporting tabs 8 by snap fasteners 11, so that a new band may be snapped in at any time. One of the fasteners is preferably 25 located adjacent the ends of the band, so that the rivet for the fastener also functions to secure the end portions of the band together. Another feature of these fasteners is that they provide 30 a pivot connection between the sweat band and supporting tabs. As a result of the sweat band and tabs both being pivoted, the tabs are free to swing from side to side to fit the particular shape 35 of the wearer's head. This flexibility of the sweat band and its mounting adds materially to the comfort of the wearer.

Head straps 7 are fastened through slots 12 provided at the upper widened ends of tabs 8, and are held by beads 13 lying back of the tabs. These beads are conveniently formed by folding 40 over the end portions of the straps. In assembling the straps, the tabs 8 with the sweat band removed may be turned end for end about their pivots to position slots 12 below the lower 45 portions of the crown. The straps may then be inserted, and the tabs turned back into position. The upper ends of the straps are then connected by a tie cord 16 passing through suitable loops formed by folding back portions of the ends of 50 the straps.

I claim:

1. A hat comprising a crown, a sweat band, a supporting tab for the band pivotally connected to the crown at a point above said band, and 55

a head strap fastened to the tab above the pivot connection.

2. A hat comprising a crown, a tab pivotally connected intermediate its ends to the crown, a sweat band fastened to the lower end of the tab, and a head strap fastened to the upper end of the tab.

3. A hat comprising a crown, a tab fastened intermediate its ends to the crown so that the ends of the tab extend freely in opposite directions from the fastening, a sweat band fastened to one free end of the tab, and a head strap fastened to the other free end of said tab. 5

LAUREN OTHO WISMAN.
